UNITED STATES PATENT OFFICE.

FRANK R. CRANE, JR., OF CHICAGO, ILLINOIS, ASSIGNOR, BY DIRECT AND MESNE ASSIGNMENTS, TO CRANE ELECTRIC SPECIALTY COMPANY, A CORPORATION OF ILLINOIS.

ELECTRIC SIGN.

1,075,767.

Specification of Letters Patent. Patented Oct. 14, 1913.

Application filed January 22, 1913. Serial No. 743,456.

To all whom it may concern:

Be it known that I, FRANK R. CRANE, Jr., a citizen of the United States, residing at Chicago, county of Cook, and State of Illinois, have invented a new and useful Improvement in Electric Signs, of which the following is a specification.

My invention relates to electric signs and particularly to signs in which individual letters or characters are grouped together on a support and individually illuminated.

My invention may be considered as an improvement over signs in which illuminating filaments are provided at intervals in the body of a letter and all connected with a current supply conductor. In such construction failure of one filament to burn properly will render the entire letter useless and the letter must be removed from the support and a new letter substituted. This procedure involves considerable expense and besides the sign is out of commission until the new letter has been applied and connected in circuit. The first cost of a sign is also considerable owing to the delicate construction of the letters.

Among the important objects of my invention are: to provide letter structure of less delicate and more simple construction; to provide letter structures blown from glass with the letter proper raised or embossed on a supporting body; to provide an arrangement whereby the letter structure may be permanently secured to a support and in which electric bulbs may be removably inserted; to provide improved means on the support for the letter structures for holding the bulbs in proper position within the structures; to provide improved circuit contact arrangement for the various bulbs; to provide improved reflector arrangement in the letter structure for reflecting the light from the bulbs through the raised letters; and in general, to provide improved and simplified construction and arrangement which will enable the sign to be kept up without the need of skilled persons and which will enable replacing of light units without loss of service and with the least cost.

In the accompanying drawings which illustrate the various features of the invention, Figure 1 is a front elevational view of a sign structure, part being broken away, Fig. 2 is an end view. Fig. 3 is a sectional view on plane 3-3, Fig. 1, Fig. 4 is a sec-

tional view on plane 4-4, Fig. 1, Fig. 5 is a front elevational view of a sign structure showing a modified arrangement, Fig. 6 is a vertical central sectional view, and Fig. 7 is an underside view showing the circuit arrangement for a letter unit.

In the drawings 10 represents a supporting base for the letter structure 11. The letter structures are blown integral from glass like bottles and comprise each a body part 12, a neck 13 and a raised or embossed letter 14. The interior of the body part forms a compartment for an illuminating means, such as an electric light bulb 15. The bulbs shown are cylindrical and elongated and of comparatively small diameter, and the letter structure bodies are oblong and of a height and width proportional to that of the letters embossed thereon. The structures shown are of the same height and width as the letters thereon although for other letters, as for example the letter I, they might be of less width.

The depth of the letter structures need be only sufficient to readily accommodate the light bulbs. The walls of the structures are of substantially uniform thickness, the embossed letters being of semi-circular cross section. The upper and side corners 16 and 17, are well rounded to provide reflector surfaces 16' and 17' for throwing the light toward the letters, these corners and the backs 18 and the bases 19 of the bodies being preferably silvered. The front walls 20 are preferably made opaque as by painting so that the light can be seen only through the letters.

The necks of the letter structures fit snugly into pockets 21 provided in the supporting base 10 and the bases 19 of the body parts abut against the top of the supporting base. In Figs. 1, 2 and 3 is shown one circuit arrangement for the light bulbs. Each bulb has a supporting socket 22 and over such socket a plug 23 of cork or rubber is slipped, the plugs fitting in openings 24 in the supporting base below the pockets 21. The openings preferably taper so that the plugs will be compressed when inserted and will rigidly secure the lamps in place with the bulbs extending into the letter structures. Secured to the underside of the base 10 are bus bars 25 and 26 which are connected with a suitable current supply circuit. The leads 27 and 28 from the lamps

are connected with the bus bars as by screws 29. With this arrangement, when a lamp burns out or breaks it can readily be disconnected from circuit and removed by without drawing its supporting plug, and a new lamp can as readily be inserted. Such replacing can be accomplished in very short time and the sign need not therefore be put out of commission for long periods as is the case where each letter structure has a plurality of light filaments permanently secured therein and it is necessary to remove the entire letter structure. Repairs on such letters are very expensive, but with application of the arrangement the expense of restoring a letter to operative condition involves at most only the cost of a new bulb and the replacing of such bulb will not require the services of an electrician but can readily be performed by the owner of the sign.

In Figs. 5, 6 and 7 is shown a modified arrangement for supplying current to the lamps in which it is not necessary to disconnect or connect wires where a lamp is to be replaced. The lamp supporting sockets 30 are of insulating material and each has secured to its outside longitudinally extending terminal strips 31 and 32 with which the lamp filament ends are electrically connected through an opening 33 in the base of the supporting socket. Openings 34 are provided in the base 10 below the letter structure supporting pockets 35 and at opposite sides of each opening are circuit terminals 36 and 37 with which the lamp terminal strips 31 and 32 engage when a lamp is inserted into the letter structure. As shown the terminals 36 and 37 have right angle extensions 36' and 37' which are secured to the underside of base 10 by screws 38, and these extensions support contact screws 39 and 40 whereby the bus conductors 25 and 26 may be electrically connected with the terminals 36 and 37. These conductors are shown diagrammatically in Fig. 6 but in practice could be arranged as shown in Figs. 1, 2 and 3. The lamp terminals 31 and 32 and the circuit terminals 36 and 37 are preferably of arcuate cross section in order to better hold the lamps rigidly in proper position within the letter structures. The terminals 36 and 37 are also preferably sprung inwardly as shown at the right of Fig. 6 so as to exert pressure against the lamp terminals to assure good electrical contact.

The lower ends 31' and 32' of the lamp terminals may be deflected over against the base of the supporting socket to be thereby better held in alignment.

With the arrangement in Figs. 5, 6 and 7, when a lamp becomes defective it need only be extracted and another lamp inserted, no manipulation of lead or circuit wires being necessary. In fact, it requires no more

skill and energy to replace a lamp in such sign than it would require to replace a lamp in any ordinary electric light socket.

I thus provide a very simple and efficient sign construction which does not require skill to operate and repair. The letter structures need never be removed and require no attention. All that is necessary for efficient upkeep of the sign is to replace defective lamps, and such replacing requires neither skill nor any length of time.

As changes and modifications may be possible which would still come within the spirit of the invention, I do not desire to be limited to the exact construction and arrangement shown and described, and I claim the following:

1. In an electrical sign, the combination of a supporting base having a plurality of pockets in its upper side, letter structures each having a neck for engaging in said pockets, said base having openings in its bottom one to each of said pockets, lamps adapted to be inserted into said letter structures through said openings and pockets, a plug for each lamp receiving the lower end thereof and adapted to engage tightly in the respective opening to securely hold the lamp in position in its structure, circuit terminals for each lamp, and current supply contacts for said terminals.

2. In an electrical sign, the combination of a supporting base having vertical openings therethrough, letter structures each having a neck on its base for fitting into the upper end of one of said openings, said structures having transparent letter areas, a lamp extending through each opening and into the corresponding letter structure, a supporting base for each lamp fitting into the lower end of the respective opening, and circuit connections for said lamps.

3. In an electrical sign the combination of a supporting base having openings extending vertically therethrough, a letter structure over each opening having a supporting neck fitting into the upper end of the opening, a lamp extending through each opening and into the letter structure thereover, a supporting plug for each lamp fitting into the lower end of the opening, terminals on each plug, and supply circuit terminals on said supporting base for receiving said lamp terminals.

4. In an electrical sign, the combination of a supporting base having an opening extending therethrough, a letter structure having a neck fitting into one end of said opening, a lamp extending through said opening and neck and into said letter structure, a supporting plug for said lamp fitting into the other end of said opening, lamp terminals on said plug, and circuit terminals in said opening with which said lamp terminals engage upon insertion of the lamp.

5. In an electrical sign, the combination of a supporting base, a letter structure mounted on said base, an opening through said base leading to said structure, a lamp adapted to be inserted through said opening and into the letter structure, terminal contacts on said lamp, and circuit terminals on said base engaged by said contacts upon insertion of the lamp.
- 10 6. In combination, a hollow letter structure having a neck, a supporting base having an opening therethrough into one end of which said neck fits, a lamp adapted for insertion into said letter structure through
- 15 said opening and neck, a supporting plug of insulating material for the lamp fitting into said opening, contacts on said plug, and circuit terminals secured in said opening and engaged by said contacts upon insertion of the lamp.
- 20
- In testimony whereof I have signed my name to this specification in the presence of two subscribing witnesses this 15th day of January, A. D. 1913, at Chicago, Illinois.
